(57) **CLAIM**

The ornamental design for a hook for use with a mounting bracket, as shown and described.

DESCRIPTION

FIG. 1 is a perspective view of a hook for use with a mounting bracket;

FIG. 2 is front view of the hook for use with a mounting bracket;

FIG. 3 is a back view of the hook for use with a mounting bracket;

FIG. 4 is a left side view of the hook for use with a mounting bracket;

FIG. 5 is a right side view of the hook for use with a mounting bracket;

FIG. 6 is a top view of the hook for use with a mounting bracket;

FIG. 7 is a bottom view of the hook for use with a mounting bracket; and,

FIG. 8 is a perspective view of the hook for use with a mounting bracket, shown in an environment of use with a mounting bracket.

The broken lines depicting the mounting bracket form no part of the claimed design.
